(57) **CLAIM**

The ornamental design for a combination power bank and charger, as shown and described.

DESCRIPTION

FIG. 1 is a front, top and right side perspective view of a combination power bank and charger showing our new design;

FIG. 2 is a front elevational view of the combination power bank and charger;

FIG. 3 is a rear elevational view of the combination power bank and charger;

FIG. 4 is a top plan view of the combination power bank and charger;

FIG. 5 is a bottom plan view of the combination power bank and charger;

FIG. 6 is a left side elevational view of the combination power bank and charger;

FIG. 7 is a right side elevational view of the combination power bank and charger;

FIG. 8 is a front, top and right side perspective view of a first component of the combination power bank and charger;

FIG. 9 is a front elevational view of the first component of the combination power bank and charger;

FIG. 10 is a rear elevational view of the first component of the combination power bank and charger;

FIG. 11 is a top plan view of the first component of the combination power bank and charger;

(Continued)

FIG. 12 is a bottom plan view of the first component of the combination power bank and charger;
FIG. 13 is a left side elevational view of the first component of the combination power bank and charger;
FIG. 14 is a right side elevational view of the first component of the combination power bank and charger;
FIG. 15 is a rear, top and right side perspective view of the first component of the combination power bank and charger when it is in use;
FIG. 16 is a front, top and right side perspective view of a second component of the combination power bank and charger;
FIG. 17 is a front elevational view of the second component of the combination power bank and charger;
FIG. 18 is a rear elevational view of the second component of the combination power bank and charger;
FIG. 19 is a top plan view of the second component of the combination power bank and charger;
FIG. 20 is a bottom plan view of the second component of the combination power bank and charger;
FIG. 21 is a left side elevational view of the second component of the combination power bank and charger;
FIG. 22 is a right side elevational view of the second component of the combination power bank and charger;
FIG. 23 is a front, top and right side perspective view of the second component of the combination power bank and charger when it is in use;
FIG. 24 is a front, top and right side perspective view of a third component of the combination power bank and charger;
FIG. 25 is a front elevational view of the third component of the combination power bank and charger;
FIG. 26 is a rear elevational view of the third component of the combination power bank and charger;
FIG. 27 is a top plan view of the third component of the combination power bank and charger;
FIG. 28 is a bottom plan view of the third component of the combination power bank and charger;

FIG. 29 is a left side elevational view of the third component of the combination power bank and charger;
FIG. 30 is a right side elevational view of the third component of the combination power bank and charger; and,
FIG. 31 is a front, top and right side perspective view of the third component of the combination power bank and charger when it is in use.
The broken lines in the drawings illustrate portions of the combination power banks and charger that form no part of the claimed design.
